James E. Cole

(57) CLAIM

The ornamental design for a flag, as shown and described.

DESCRIPTION

FIG. 1 is a front view of a flag; and

FIG. 2 is a top view of the design of FIG. 1, where the bottom view is a mirror image of the top view;

FIG. 3 is a first side view of the design of FIG. 1; and,
FIG. 4 is a second side view of the design of FIG. 1.

The broken lines showing environmental structure are for illustrative purposes only and form no part of the claimed design.
